US00D581537S

(12) **United States Design Patent**
Blouin et al.

(10) **Patent No.:** **US D581,537 S**
(45) **Date of Patent:** **** Nov. 25, 2008**

(54) **SPINAL IMPLANT**

(75) Inventors: **Felix Blouin**, Sterling Forest, NY (US);
Bruce Robie, Glen Rock, NJ (US)

(73) Assignee: **Zimmer Spine, Inc.**, Minneapolis, MN (US)

(**) Term: **14 Years**

(21) Appl. No.: **29/277,257**

(22) Filed: **Feb. 20, 2007**

(51) **LOC (8) Cl.** **24-03**

(52) **U.S. Cl.** **D24/155**

(58) **Field of Classification Search** **D24/155, D24/156, 157; 623/17.11, 16.71; D8/391-393, D8/382, 354; 606/246, 247, 248, 249, 258, 606/267, 280, 70, 71, 283, 299, 166, 903, 606/905, 906, 286, 396; D15/139**

See application file for complete search history.

(57) **CLAIM**

The ornamental design for a spinal implant, as shown and described.

DESCRIPTION

FIG. 1 is a perspective view of a spinal implant showing our new design;

FIG. 2 is a right side elevation thereof, the side opposite being a mirror image;

FIG. 3 is a top end elevation thereof, the end opposite being a mirror image;

FIG. 4 is a rear elevation thereof; and,

FIG. 5 is a front elevation thereof.

The broken lines shown in the drawing are included for the purpose of illustrating unclaimed structure and form no part of the claimed design.
